[57] CLAIM

The ornamental design for an overflow tray for a car battery, as shown.

DESCRIPTION

FIG. 1 is a perspective view of the overflow tray for a car battery;

FIG. 2 is a plan view taken in the direction of arrow II of the tray of FIG. 1;

FIG. 3 is a sectional view taken along arrows III of FIG. 2;

FIG. 4 is a bottom plan view taken in the direction of arrow IV of FIG. 1;

FIG. 5 is a view of the tray of FIG. 1 taken in the direction of arrow V;

FIG. 6 is a view of the tray of FIG. 1 taken in the direction of the arrow VI;

FIG. 7 is a view of the tray of FIG. 1 taken in the direction of the arrow VII;

FIG. 8 is a view of the tray of FIG. 1 taken in the direction of the arrow VIII; and

FIG. 9 is a sectional view of FIG. 2 taken along arrows IX.
